UNITED STATES PATENT OFFICE.

WILLIAM BRIDGES, OF DARBY, PENNSYLVANIA.

BUILDING BLOCK.

Application filed October 31, 1922. Serial No. 598,091.

To all whom it may concern:

Be it known that I, WILLIAM BRIDGES, a citizen of the United States, residing at Darby, in the county of Delaware and State of Pennsylvania, have invented certain new and useful Improvements in Building Blocks, of which the following is a specification.

My invention relates to wall construction and more particularly to building blocks 10 adapted especially for facing brick walls or frame structures.

The object of the invention is to provide novel and simple building blocks, which may be easily laid, afford means of efficiently 15 anchoring them to each other and to a brick wall or the studding of a frame structure, and provides horizontal and vertical dead air spaces between the facing wall and supporting wall or frame structure.

20 This object, and other advantageous ends which will be described hereinafter, I attain in the following manner, reference being had to the accompanying drawings in which

Figure 1 is a plan view of a building 25 block of my invention.

Figure 2 is a rear view of a block,

Figure 3 is a side elevation,

Figure 4 is a fragmentary side elevation 30 showing a brick wall faced with the improved block,

Figure 5 is a plan view of the structure shown in Figure 4,

Figure 6 is a fragmentary rear elevation 35 showing the manner of facing a frame building structure with the improved block, and

Figure 7 is a horizontal sectional view taken on the line 7—7 of Figure 6.

In the drawings, 10 is a block comprising 40 a thin rectangular body 11, preferably molded of concrete. The body is preferably longer than it is high and ends 12 have grooves 13 extending throughout their lengths, midway between and parallel to the front and rear faces of the body. Tying 45 projections 14 are molded on the back of the body at each end midway between the top and bottom edges. These projections are preferably rectangular and elongated vertically with their top and bottom faces 50 15 and 16 spaced from the top and bottom edges 17 and 18 of the body a distance substantially equal to one-half the height of the projection, and their outer faces 19 flush with ends 12. Projections 14 are preferably made of a width corresponding to the

width of a brick and of a height corresponding to the thickness of a certain number of bricks together with the mortar used to bind them.

In Figures 4 and 5 of the drawings, the 60 blocks are shown applied as a facing to a brick or supporting wall. The wall is designated at 20 and has bricks 21 laid end to end. The blocks are laid on edge so that the ends abut, and grooves 13 in abutting 65 ends 12 are disposed opposite each other to mate and form an opening in which mortar or cement is poured, as indicated at 22, to form locking means between the ends of the blocks. The outer faces 19 of projections 70 16 contact and all of the abutting faces are joined by mortar or cement as in laying masonry or bricks. Certain bricks 23 which will hereafter be called top and bottom bricks, are laid crosswise to bricks 21 to 75 underlie and overlie projections 14 and are connected by a suitable binding to faces 15 and 16.

By this arrangement, an efficient connecting means is provided, between the brick 80 wall and the blocks constituting the facing, so that the blocks are firmly held in position.

The arrangement also produces a hollow wall structure in which a series of vertical and horizontal dead air spaces 24 are provided between the wall and the facing. The size of the air spaces is determined by the size of the projections 14 at the ends of the blocks and the top and bottom bricks 23 which tie the blocks to the wall.

In Figures 6 and 7 of the drawings, the 85 blocks are shown employed as a facing for a frame building structure in which 25 are the vertical timbers or studding against which the blocks 10 are laid, bound and connected as previously described. Horizontal timbers 26 are connected to studding 25 as indicated at 27, to bindingly engage the top 90 and bottom faces of projections 14 and form top and bottom parts or tying means between the blocks and the frame building structure. When laths are applied to the studding at the inside, and plastered over, dead air spaces are provided between the blocks and the wall structure separated by 105 the vertical timbers or studding.

While I have described my invention as taking a particular form, it will be understood that the various parts of my invention may be changed without departing from the 110

spirit thereof, and hence I do not limit myself to the precise construction set forth, but consider that I am at liberty to make such changes and alterations as fairly come 5 within the scope of the appended claims.

Having thus described my invention, what I claim as new and desire to secure, by Letters Patent is:—

1. A building block comprising a flat body 10 with top and bottom longer than its ends, each end having a groove throughout its length, and rectangular projection on the rear face of the block with their outer faces flush with the ends of the body and their 15 top and bottom faces spaced from the top and bottom.
2. A building block comprising a thin rectangular body having integral projections upon one face midway of its top and bottom 20 edges and flush with the ends of the body, the projections being spaced from the top and bottom edges a distance substantially equal to one-half of the height of the projections.
3. A wall structure comprising a supporting wall; a facing wall; projections on the facing wall; a top part projecting from the supporting wall and anchored to the top of each projection, and a bottom part projecting 25 from the supporting wall and anchored to the bottom of each projection, the top part

and bottom part on the supporting wall being spaced to provide a dead-air space.

4. A wall structure comprising a brick wall; a facing wall; projections on the 35 facing wall; a top brick projecting from the brick wall and anchored to the top of each projection, and a bottom brick projecting from the brick wall and anchored to the bottom of each projection, the top brick on 40 one projection being spaced from the bottom brick on the adjacent projection to form a dead air space.

5. A wall structure comprising a brick wall; a block facing wall; projections on 45 each block midway between its top and bottom edge; a top brick projecting from the brick wall and anchored to the top of each projection, and a bottom brick projecting from the brick wall and anchored to the 50 bottom of each projection, the top wall on one projection being spaced from the bottom brick of the adjacent projection to form a dead air space.

In testimony whereof I have signed my 55 name to this specification in the presence of two subscribing witnesses.

WILLIAM BRIDGES.
